ATMOSPHERIC VAPORIZER

Robert C. Enger, Buffalo, and Ford R. Park, Jr., Snyder, N. Y., assignors to Union Carbide Corporation, a corporation of New York

Application July 24, 1953, Serial No. 370,157

2 Claims. (Cl. 62—1)

The present invention relates to apparatus for vaporizing volatile liquids and, more particularly, to apparatus for vaporizing volatile liquids such as oxygen, nitrogen and the like, having boiling point temperatures below 233° K. at atmospheric pressure.

Could air at optimum temperature and relatively humidity (at least 70° F. and not more than 50% relative humidity) be employed, the problem of providing a highly efficient atmospheric vaporizer would indeed be a relatively easy one. However, due either to their size or conditions of use, for example liquefied gas transporting equipment, such vaporizers are usually located out-of-doors where they are subjected to extreme atmospheric conditions which greatly complicate the problem of providing a simple and highly efficient atmospheric vaporizer. During certain periods of the winter, severe atmospheric conditions are encountered wherein the air temperature and relative humidity are such as to cause heavy ice and frost deposits to form on the coils and fins of finned-tube type atmospheric vaporizers operating under these conditions. These ice and frost deposits are in some cases sufficiently thick to block the circulating air passages and greatly reduce the heat transfer to the volatile liquid thereby causing a failure in vaporization.

The worst operating conditions for atmospheric vaporizers are in the 30–40° F. ambient air region with high (100%) relative humidity, as heavy ice deposits are formed in this range. The usual severe winter weather of 0° F. or below is not as critical, as the bulk of the resultant frost deposit is blown off the heat transfer surfaces by the vaporizer fan.

The power requirements of atmospheric vaporizers are considerably less than other vaporizing means such as steam and electricity; consequently, such vaporizers may be practically installed in mobile volatile liquid transport units where it is desired to transport the payload as a liquid, but distribute it as a gas with a limited power supply.

It is, therefore, an object of the present invention to provide a simple and highly efficient atmospheric vaporizer through which atmospheric air and the liquid to be vaporized are passed in heat exchange relation.

Another object is to provide such an atmospheric vaporizer which will successfully vaporize volatile liquids even under the most adverse winter atmospheric conditions to be encountered.

A still further object is to provide such an atmospheric vaporizer having a size and weight sufficiently small for ease in portability.

Other aims and advantages of the invention will be apparent from the following description and appended claims.

In the accompanying drawings:

Fig. 1 is a side view, mainly in cross-section, of an atmospheric vaporizer embodying the present invention, the section being taken along the line 1—1 of Fig. 2;

Fig. 2 is a front view, partly broken away, of the atmospheric vaporizer of Fig. 1;

2

Fig. 3 is an elevational view, partly in section, of a modified tube arrangement to be employed in an atmospheric vaporizer embodying the invention which is capable of below critical pressure operation; and

5 Fig. 4 shows a series of curves graphically representing the relationship between heat transfer rate, fin thickness, and coil spacing for two of the different materials which may be employed as the fin and coil material in the atmospheric vaporizer of the present invention.

10 In accordance with the present invention, and referring to the embodiment shown in Figs. 1 and 2 of the accompanying drawings, an atmospheric vaporizer V is provided having an outer casing 1, a plurality of fins 2 of copper, aluminum or other suitable material, arranged parallel to

15 each other and to the axis of the outer casing, a plurality of serpentine tubes 3 of copper or other suitable material each secured to fin 2, and connected in parallel, and a fan 4 positioned at one end for forcing a stream of atmospheric air through the space between the plurality of fins 2 and tubes 3.

20 The tubes are secured against the fins so as to provide suitable metallic heat conductive paths between the tubes and fins; for example, the tubes may be metal-bonded to the fins by soldering or brazing, depending on the materials used for the tubes and fins.

25 The inlet and outlet ends of the plurality of serpentine tubes are connected with an inlet manifold 5 and an outlet manifold 6, respectively. At both the inlet and outlet ends of serpentine tubes 3, expansion loops or bends 7 and 8, respectively, are provided to allow the system to adjust to any mechanical expansion or contraction due to changes in temperature. Shaft support bracket means 9 is provided to support the fan shaft at one end of the outer casing. The members 10 are provided to guard

30 against the passage of objects into the fan, as well as to help structurally strengthen the extension 11 of outer casing 1, and support shaft support means 9.

35 The inlet tube arrangement illustrated in Figs. 1 and 2 is suitable for vaporizing and superheating a volatile liquid at any pressure, but is preferred for operation above the critical pressure.

40 It has been found that there are many variables encountered in the design of an atmospheric vaporizer of this type which affect the total heat transfer from air to a volatile liquid to be evaporated and superheated in the tubes of an atmospheric vaporizer of this type. In addition to this, the temperature of the volatile liquid and that of the atmospheric air also greatly affects the total heat transfer.

45 The following equation, which correlates total rate of heat transfer from air to the fluid to be heated in the atmospheric vaporizer of the present invention with other variable parameters and conditions, has been 50 theoretically developed to correlate results obtained by testing atmospheric vaporizers of this type under widely varying conditions:

$$Q = \frac{N}{2L} \frac{AB(T_A - T_V)t^{1/2} \operatorname{Tanh} \sqrt{\frac{2h_A}{kt}} L}{A + Bt^{1/2} \operatorname{Tanh} \sqrt{\frac{2h_A}{kt}} L}$$

wherein:

60 Q =total rate of heat transfer from air to volatile liquid (B. t. u./hr./sq. ft.).

k =coefficient of thermal conductivity of fin (B. t. u./hr. sq. ft./° F./ft.).

T_A =inlet atmospheric air temperature (° F.).

T_V =inlet volatile liquid temperature (° F.).

t =fin thickness (ft.).

h_A =air side film coefficient (B. t. u./hr./sq. ft./° F.).

h_v =volatile liquid side film coefficient (B. t. u./hr./sq. ft./° F.).

$L=\frac{1}{2}$ space between adjacent tubes (ft.).

a =volatile liquid side area for 1 foot of length (ft.²).

$$A = \frac{h_v \cdot a}{2}$$

$$B = \sqrt{2h_A \cdot k}$$

N =number of vaporizer fins.

This equation is graphically represented in Fig. 4 of the drawing which shows the relationship between rate of heat transfer and fin thickness for a series of tube spacings. The curves are for copper and aluminum tubes and fins, but the equation may be applied to fin-tube atmospheric vaporizers of any material. It is also pointed out that the total rate of heat transfer is equal to the numbers of fins employed in the vaporizer multiplied by the heat transfer rate per fin.

The above-stated equation does not include fin spacing as a variable factor as it is relatively easy to empirically determine this factor for specific applications. It is necessary to position the fins sufficiently far apart to maintain internal air passages through the vaporizer assembly during severe weather conditions in which the fins are partially covered with frost or ice.

For operation below the volatile liquid critical pressure, it is sometimes desirable to increase the liquid-vapor disengaging space in the inlet tubes. This prevents "priming"—the blowing of liquid slugs through the tubes causing pressure surges. Another advantage of increased liquid-vapor disengaging space is the percentage increase of vaporization near the inlet, thus releasing a larger portion of the remaining fin-tube heat transfer area for superheating the gas. This results in larger overall heat transfer than would be obtainable in a similar sized vaporizer without the increased liquid-vapor disengaging space.

Fig. 3 illustrates such a modified tube arrangement that is applicable for any pressure but preferred for operation below the critical pressure of the liquefied gas. Elements have been assigned reference numbers by adding 100 to the equivalent elements of Figs. 1 and 2.

The embodiment of the invention shown in Fig. 3 consists of a plurality of fins 102, a serpentine tube coil 103 positioned on and bonded to each of the fins, inlet manifold means 105 at the bottom of the vaporizer, and enlarged liquid boiling tubes 112. In Fig. 3, two inlet tubes 112 are shown to more fully utilize the available fin heat transfer area. It is to be understood that any desired number of inlet tubes may be used. The inlet manifold 105 supplies the volatile liquid to the tubes 112 which in turn are connected by branch connections 122 to the lower end of tubes 103. The vaporized liquid is collected by the outlet manifold at the top of the vaporizer in a manner similar to that employed in the embodiment shown in Figs. 1 and 2.

The embodiment of the invention shown in Figs. 1 and 2 may be operated either horizontally or vertically as the physical arrangement demands. The Fig. 3 embodiment must be placed vertically, as shown. A horizontal orientation would not utilize the large inlet liquid-vapor disengaging space, and priming would cause poor heat transfer.

Although the vaporizer shown in Figs. 1 and 2 is of the counter-current type, it is to be understood that the invention is equally applicable to a co-current relationship between the flow of volatile liquid and atmospheric air. The circulating air is cooled almost linearly and very slowly so that the direction of air flow is determined by the most practical mechanical arrangement.

The vaporizer of the present invention may be operated

with or without forced air circulation, depending on the capacity and rate at which the volatile liquid is to be vaporized. If the required capacity is sufficiently low, natural air circulation may be used with no external power source. On the other hand, with a high capacity requirement, an external power source is required to drive the fan or other means of obtaining forced air circulation.

It has been found that atmospheric vaporizers in accordance with the present invention can successfully operate out-of-doors under the severest weather conditions. For example, an atmospheric vaporizer of the type herein disclosed, having a capacity of 3,000 cu. ft. per hr. at normal temperature and pressure, was built and successfully operated for a continuous 43-hour period with an ambient air temperature between 25° F. and 40° F. and the relatively humidity above 68%. Although ice and frost deposited on the coils and fins under these conditions, the heat transfer was sufficient to vaporize the required quantity of liquid oxygen, and the ice formation did not build up sufficiently to block the atmospheric air passages between the fins. It is pointed out that if the volatile liquid flow to the atmospheric vaporizer is reduced sufficiently the unit could be continuously operated for an indefinite period.

What is claimed is:

1. In an atmospheric vaporizer having a plurality of spaced parallel fins of heat conducting material and a heat conducting fluid conduit having a plurality of serpentine bends positioned in heat exchange contact with each of said plurality of fins over substantially all of the length of said fins, the method of operation which comprises concurrently passing a quantity of volatile liquid into the same ends of each of said fluid conduits; passing atmospheric air between and in heat exchange contact with said plurality of spaced parallel fins; collecting vaporized volatile liquid from the opposite ends of said heat conducting fluid conduits; and maintaining each of the variable heat transfer parameters at a value to provide a total heat transfer in accordance with the equation:

$$Q = \frac{N}{2L} \frac{AB(T_A - T_v)t^{1/2} \operatorname{Tanh} \sqrt{\frac{2h_A}{kt} L}}{A + Bt^{1/2} \operatorname{Tanh} \sqrt{\frac{2h_A}{kt} L}}$$

wherein:

Q =total rate of heat transfer from air to volatile liquid (B. t. u./hr./sq. ft.)

k =coefficient of thermal conductivity of fin (B. t. u./hr./sq. ft./° F./ft.)

T_A =inlet atmospheric air temperature (° F.)

T_v =inlet volatile liquid temperature (° F.)

t =fin thickness (ft.)

h_A =air side film coefficient (B. t. u./hr./sq. ft./° F.)

h_v =volatile liquid side film coefficient (B. t. u./hr./sq. ft./° F.)

a =volatile liquid side area for one foot of length (sq. ft.)

$$A = \frac{h_v \cdot a}{2}$$

$$B = \sqrt{2h_A \cdot k}$$

N =number of vaporizer fins

2. An atmospheric vaporizer for vaporizing liquefied gas comprising a plurality of spaced parallel fins of heat conducting material; a heat conducting parallel-flow fluid conduit having a plurality of serpentine bends, positioned in the air space between an adjacent pair of said plurality of spaced fins, and secured on one side in heat exchange contact with one of said fins over substantially all the length of the fins to increase the contact area between said fluid conduits and said fins; inlet manifold means communicating with one end of each of said fluid

conduits for introducing a volatile liquid into the same end of each of said fluid conduits; outlet manifold means communicating with the other end of said fluid conduits for collecting vapors of said volatile liquid from said plurality of fluid conduits; means for passing atmospheric air unidirectionally in parallel-flow streams between and in heat exchange contact with said plurality of spaced parallel fins; and a plurality of parallel-flow conduit means, one associated with each of said fins, positioned in heat exchange contact therewith and communicating between said inlet manifold means and one of said fluid conduits, said plurality of parallel-flow conduit means

of substantially greater total cross-sectional area than that of each of said fluid conduits.
